DESIGN FOR A DRESSER BASE OR SIMILAR ARTICLE

Wesley A. Rundell, Louisville, Ky.

Application June 8, 1944, Serial No. 113,924

Term of patent 14 years

(Cl. D33—6)

To all whom it may concern:

Be it known that I, Wesley A. Rundell, a citizen of the United States, residing at 667 Lindell, Louisville, in the county of Jefferson and State of Kentucky, have invented a new, original, and ornamental Design for a Dresser Base or Similar Article, of which the following is a specification, reference being had to the accompanying drawing, forming part thereof.

I claim:

The ornamental design for a dresser base or similar article, substantially as shown and described.

WESLEY A. RUNDELL.
